REVERSE CIRCULATION ROTARY ROCK BIT

Chester B. Day, Loveland, Colo.

Application February 8, 1956, Serial No. 564,161

16 Claims. (Cl. 255—306)

The present invention relates to the well drilling industry, and more particularly to a revolving cutter rotary rock drill for drilling large diameter irrigation wells or the like.

The invention provides cutter means for simultaneously forming a pilot hole and a full diameter controlled counterbore. Rotary drills having pilot hole drilling means and co-operating roller reamer cutters carried in upwardly spaced relation above the pilot for enlarging the bore to the desired diameter are well known to those skilled in the art, but certain disadvantages have been experienced in the use of such drills because of the size and weight thereof, and tendency to veer from the perpendicular. The difficulties experienced in drilling of off-line bores has resulted in the inability to insert casing into the bore, which necessitated enlarging the bore to a much larger diameter than the diameter of the casing to be inserted therein.

Tests have proven that five or six angularly disposed rolling cutters or reamers converging downwardly and used in co-operation with a pilot bit, tend to work against themselves horizontally and produce a straighter hole. It is therefore the principal object of this invention to provide a drill structure wherein weight and mass are held at a practical minimum and yet accurate straight well boring is assured.

The present drill is designed primarily to be used in connection with reverse circulation well drilling. This is a method wherein a centrifugal pump is connected to the drill pipe adjacent the surface of the earth, and fluid is drawn out of the top of the drill string. A water level is maintained close to the surface of the earth within one of the slush pits in communication with the top of the drilled bore. As water is pumped from the drill pipe and into the pits, the water flows by gravity into the top of the drilled bore and down around the drill pipe to the bottom of the bore, and then upwardly through the drill bit and drill pipe to complete the cycle. In seeking its level within the drilled bore and the drill pipe, the water flows across the drill cutters and through openings in the bottom of the drill with sufficient velocity to lift or carry fragments of rock or other earth formations, almost as large as the inside diameter of the drill pipe, to the surface of the earth where these cuttings are picked up by the pump and exhausted into the pits. Thus, a continuous stream of fluid is maintained downwardly through the annulus of the well bore around the drill pipe and upwardly through the bore of the drill pipe. This reverse circulation method of drilling has certain advantages over the conventional method of circulating the drilling fluid downwardly through the bore of the drill pipe and upwardly in the annulus of the well bore around the pipe to the pits at the earth's surface. The principal advantage of the reverse circulation method lies in the elimination of the amount of heavy equipment used, such as mud-hog pumps and power means for driving the same to force fluid downwardly through the rotating drill pipe and back to the earth's surface around the pipe. Another advan-

2

tage arises from the fact that reverse circulation permits the flow of fluid to cleanse a plurality of cutters of a drill, thus making a relatively large bore in one operation without the necessity of drilling a pilot hole and reaming it out to the desired size. The reverse circulation method of drilling is most effective in depths ranging up to approximately 900 feet, at the present time.

More particularly the invention resides in providing a drill comprising a longitudinal tubular body having a relatively large bore and adapted to be disposed vertically and connected to the lower end of a drill string and rotated about its longitudinal axis. A plurality of support members are each rigidly connected at their upper ends to the body intermediate its ends in equidistantly radially spaced relation about its axis and project angularly outwardly and downwardly and all terminate in a common horizontal plane at their lower ends in outward equidistantly radially spaced relation from the lower end of the body. A like plurality of truncated conical counterboring cutters are rotatably journaled between the lower extremity and the adjacent side of the bottom of the body. The axis of the respective truncated cutters all lie within a conical surface generated about the longitudinal axis of said body. A conventional triple rotating-cone pilot cutter is rigidly connected to the lower end of the body. A fluid course, extending through the pilot cutter, communicates with the bore of the body.

Another object of the invention is to provide a drill head of this class, wherein a triple rotating-cone cutter is mounted on the lower end of the body and acts as a pilot cutter, and a single rotating cutter is mounted between the lower extremity of each support member and the adjacent side of the body in spaced relation above the pilot cutter with the respective axis of the single cutters all lying within a conical surface generated about the longitudinal axis of the body.

Another object is to provide a drill of this class, wherein the diameter of the tubular body and the sizes of the support members are such that a clear space is provided between the wall of the body and each support member.

An additional object is to provide a drill head of this class which has the rotating cutters thereof arranged in spaced-apart relation relative to each other and to adjacent parts for permitting free circulation of fluid therebetween.

Yet another object is to provide a rotary drill head of this class, wherein the arrangement and relative sizes of the cutters thereof results in the pilot cutters cutting approximately 40 percent of the hole, while the counterboring cutters form an annular bore around and slightly overlap the pilot hole and cut the remaining 60 percent of the hole.

Still another object is to provide a drill head of this class in which the axis of the respective counterboring cutters all lie within a conical surface generated about the longitudinal axis of the longitudinal body, and wherein the said conical surface converges downwardly toward the lower end of the body, disposing the lower cutting surfaces of the counterboring cutters in a similar conical surface, thus keeping the drill centered for a more accurate straight bore.

A further object is to provide a drill of this class, wherein means is provided for directing fluid within the drilled bore downwardly against the cutting teeth in a washing action to cleanse the same of formation cuttings.

Yet another object is to provide a drill of this class which may be removably connected to the lower end of a rotating drill string, and which is sturdily constructed, and wherein the cutting teeth thereof may be re-

moved and replaced, thereby adding considerably to the life of the drill frame.

Other objects will be apparent from the following description when taken in conjunction with the accompanying two sheets of drawings, wherein:

Figure 1 is a side elevational view of the device in operating position, with one of the cutters and its support broken away for clarity;

Figure 2 is a bottom view of the drill with the pilot cutter removed therefrom;

Figure 3 is a vertical cross sectional view of the drill, per se;

Figure 4 is a fragmentary elevational view of one of the rotating-cone pilot cutter support arms;

Figure 5 is a vertical cross sectional view taken substantially along line 5—5 of Fig. 4;

Figure 6 is a vertical cross sectional view taken substantially along line 6—6 of Fig. 3; and

Figure 7 is a fragmentary top view of one of the support members connected to the tubular body, the body being shown in cross section.

Like characters of reference designate like parts in those figures of the drawings in which they occur.

In the drawings:

Referring more particularly to Fig. 1, the reference numeral 10 indicates, as a whole, the device which is connected to the lower end of a rotary drill string 12. Water or drilling fluid 14 from a pit, not shown, adjacent the surface of the earth enters the annulus of the drilled bore 16 around the drill pipe and flows downwardly by gravity in the direction of the arrows through the bottom of the device 10 in a manner more fully described hereinbelow, and upwardly through the bore of the drill pipe 12, from which it is removed through the kelly or drive joint and the swivel, by a suction pump, not shown. The above description is conventional with reverse circulation methods of drilling and is given here only to set forth the fundamentals of this method of drilling for which the present invention is primarily designed.

Referring now to Fig. 3, it may be seen that the device 10 comprises a vertically disposed tubular body 20, open at both ends, providing a fluid course 21 therethrough and having a flanged upper end 22 for connection with the drill pipe 12. The drill pipe illustrated has a relatively thin wall and features flanged connections 13 rather than screw-threaded tool joints to add rigidity to the drill string. Diametrically the body 20 is substantially equal to the drill pipe 12, and the bore 21 of the body is in alignment with the bore of the drill pipe. It is to be understood, of course, that conventional threads and couplings may be used for connecting the drill pipe to the drill 10 if desired.

A plurality of support members 24 are rigidly connected to the periphery of the body 20, intermediate its ends, in equidistantly radially spaced-apart relation about its axis. The members 24 extend angularly outwardly and downwardly in diverging relation from the periphery of the body 20, and all terminate in a common horizontal plane extending radially from the body 20 and above the lower end 26 of the body. In the preferred embodiment, the members 24 are substantially rectangular in cross section having a transverse width substantially equal with relation to the diameter of the bearing race of a cutter to be connected thereto, and each of the members are arcuately curved on substantially the same radius with relation to the bore the device is designed to cut, as is more clearly illustrated in Fig. 6, with the exception of the inwardly disposed surface of the depending end which is substantially flat, for the purposes which will presently be apparent.

A centrally bored plate-like flange 28 is rigidly connected to the periphery of the body 20 adjacent its lower end 26. The periphery of the flange 28 is provided with a like plurality, with relation to the members 24, of

straight edge portions 29 in co-operating parallel relation with the lower end portion of the inwardly disposed flat surface of each respective member 24. The length of the straight edge portion 29 is preferably substantially equal with relation to the diameter of the spindle of a cutter to be attached thereto, as is more fully explained hereinbelow. A truncated conical cutter 30 is rotatably journaled and extends substantially the entire distance between the lower extremity of each member 24 and the straight portion 29 of the flange 28. Each cutter 30 comprises a spindle 32, bearings 34 carried in races at opposing ends of the spindle, and a truncated conical toothed shell 37 adapted to revolve on the bearings. The assembled spindle 32 and bearing race 33 is rigidly welded in place at each end, as at 36, between the adjacent flat inner surface of the member 24 and the co-operating straight edge portion 29 on the flange 28, with the longitudinal axis of the spindle lying within a conical surface generated about the longitudinal axis of the body. The teeth 38 of the cutters 30 are arranged in radially equidistantly spaced-apart wedge shaped rows disposed longitudinally of the cutter. The ends of each respective row of teeth 38 are cut off, as at 39, to provide clearance between the same and the adjacent parts of the drill. The outwardly disposed end of each row of teeth 38 projects slightly beyond the radially outward limit of the respective member 24 for cutting a bore slightly larger diametrically than the drill, in order that the same may rotate freely within the walls thereof.

A multiple cone pilot cutter, preferably a triple cone cutter 40, is rigidly connected, as by welding the cutter head or frame 42, to the lower surface of the flange 28. The triple cone cutter 40 is substantially conventional with such cutters, except for the head 42 which has a central bore for co-operative communication with the bore 21 of the body 20 to provide a fluid course therethrough. The cutter head 42 has three equidistantly radially spaced depending arms 44, to each of which is rigidly connected a cone spindle 46 which journals a toothed cutting cone 48 by bearings 50. The spacing of the cones 48 is such that the cutting surfaces on the same lie in spaced-apart relation so that lumps of drilled formation may be carried upwardly therebetween by the flowing action of the drilling fluid 14. As illustrated more clearly in Figs. 4 and 5, a lip or fillet 52 is formed of each side of the arm 44 to form a recess, as at 54, at the angular juncture of the arm 44 with the cutter head 42. The recess 54 is necessary to provide clearance of the teeth at the base of the cone cutter 48, and the filleted corner 52 acts to direct the drilling fluid 14 downwardly to flow across the teeth of the cone cutters 48 to clean the same and remove the formation cuttings, not shown. At least one of the cone cutters has a tip 56 extending at least to the vertical axis of the body 20 to break the core formed by the two other cones 48. The cutter 40 cuts a substantially flat bottomed hole. Diametrically the ratio between the pilot cutter 40 and the annular ring formed around the same by the truncated cutters 30, may be varied in proportion with the diameter of the drilled bore desired, as long as the pilot cutter 40 cuts at least 40 percent of the hole. Five cutters 30 are illustrated in the drawings which is the preferred number for drilling holes 27 to 34 inches in diameter. Six cutters 30, and similarly six support members 24, are desired for holes 36 to 48 inches in diameter, to maintain the desired cutting ratio and more efficiently drill the formations. It is important that the outwardly projected limit of the teeth of each cone cutter 48, and the inwardly projected limit of the teeth 38 of the single cutters 30, overlap slightly to completely drill all the encountered formation. Similarly it is desirable that the cutter 40 depend from the lower end of the body 20 a sufficient distance so that a line 70 drawn between the outwardly projected limit of the teeth on the cone cutter 48, and the outwardly projected limit of the teeth of the cutters

30, substantially forms an angle of 30 degrees with relation to a horizontal plane indicated by the line 71, extending radially outwardly from the axis of the body.

In order to insure a washing action across the teeth 38 of the truncated cutters 30 by the drilling fluid 14, the space formed between each support member 24 and the wall of the body 20 is substantially filled by a web 60 rigidly connected to the respective arm and the wall of the body 20. The web 60 is helically joined to the wall of the body, as more clearly illustrated in Fig. 7, wherein the dotted lines 62 indicate the top of the web, and the dotted lines 64 indicate the bottom or depending edge of the same lying in relatively close spaced parallel relation with the upwardly disposed surface of the teeth 38 of the revolving cutters 30. The helix of the web connection to the body winds upwardly toward the left, as seen in Fig. 1, so that as the drill is rotated clockwise, as shown by the arrow 72 (Fig. 7), the drilling fluid is urged downwardly, as indicated by the arrow 73 (Fig. 3), by the surface of the web against the teeth 38, and against the direction of rotation of the cutters, by the depending edge 64. Thus, as the drill is rotated and the cutters revolve, the webs 60 create a washing action directed toward the teeth of the respective cutters to remove the formation cutting therefrom and circulate the same downwardly to the lower end 26 of the body 20, as shown by the direction arrows in Fig. 3, and thence upwardly to the surface of the earth.

Referring to Fig. 2, it may be seen that the periphery of the flange 28 is arcuately formed inwardly between each pair of straight edge portions 29, as at 66, which allows for more freedom of flow of the drilling fluid 14 downwardly between the adjacent cutters 30, and directs the fluid toward the multiple cone pilot cutter head 42.

The respective cutters 48 and 30 are removed for repair or replacement by the use of a cutting torch which is conventional with rotary rock bits.

Obviously the invention is susceptible to some change or alteration without defeating its practicability, and I therefore do not wish to be confined to the preferred embodiment shown in the drawings and described herein, further than I am limited by the scope of the appended claims.

I claim:

1. A counterboring rotary drill, comprising: a vertically disposed tubular body having the upper end thereof adapted to be connected to the lower end of a drill string and rotated therewith; a plurality of support members each rigidly connected at one end to the periphery of said body in equidistant radially spaced relation about its axis and extending angularly outward and downward therefrom intermediate the ends of said body and terminating in a common horizontal plane at their lower ends adjacent the lower end of said body in outward equidistantly spaced relation therefrom; a like plurality of spindles extending between and connected with the lower extremity of each said support member and the lower end of said body; a like plurality of truncated conical cutters journaled by said spindles, the axis of the respective truncated cutters lying within a conical surface generated about the longitudinal axis of said body; and a triple cone cutter having a frame, said frame rigidly mounted on the lower extremity of said body, said triple cone cutter frame having an opening therethrough in communication with the bore of said body, the radially outward projected limit of each said truncated cone cutter extending only a short distance outwardly of the radially outward extending limit of the support member which carries the particular truncated cone cutter to provide circulation clearance between said members and the bore wall.

2. Structure as specified in claim 1, in which the length of each truncated conical cutter is such that the same will

make an annular cut slightly overlapping inwardly the cut made by said triple cone pilot cutter.

3. Structure as specified in claim 1, in which a plane contacting the outwardly projected lower limit of each respective truncated conical cutter, and each triple cone pilot cutter, is disposed substantially at an angle of 30 degrees with relation to a horizontal plane extending radially with relation to the axis of said body.

4. A reverse circulation rotary drill, including: an open-ended vertically disposed tubular body, said body having a flanged upper end adapted to be connected to the lower end of a drill string and rotated therewith; a plurality of support members each rigidly connected at one end to the periphery of said body in equidistant radially spaced relation about its axis and angularly extending outward and downward therefrom intermediate the ends of said body, said support members terminating in a common horizontal plane at their lower ends in outward equidistant radially spaced relation from the lower end of said body; a centrally bored plate rigidly connected to the periphery of said body adjacent its lower end, a like plurality of spindles extending between and connected with the lower extremity of each said support member and the periphery of said plate, a like plurality of truncated conical cutters journaled by said spindles; the axis of the respective truncated cutters lying within a conical surface generated about the longitudinal axis of said body; a pilot cutter head rigidly mounted on the lower end of said body, said pilot cutter head having three downwardly and inwardly projecting radially spaced-apart spindles; conical cutters rotatably carried by said cutter head spindles, the apex of at least one conical cutter extending to the vertical axis of said body; and means for directing fluid within the drilled bore against the teeth of said truncated conical cutters and said conical cutters in a washing action for cleaning the same.

5. Structure as specified in claim 4, in which the means includes a helically disposed web joining the upper end portion of each said support member with the adjacent portion of said body, the depending edge of each said web lying in relatively close spaced relation with the upwardly projecting teeth of each particular truncated conical cutter, whereby rotation of said drill causes said webs to direct fluid within the drilled bore downwardly against said rotating truncated conical cutters.

6. Structure as specified in claim 4, in which the means includes depending lips carried by said pilot cutter head for partially enveloping the upwardly projecting teeth of the base end of each respective cone cutter, whereby fluid within the drilled hole is directed downwardly across the teeth of that particular cone cutter as the drill is rotated.

7. Structure as specified in claim 4, in which the length of each truncated conical cutter is such that the same will make an annular cut slightly overlapping inwardly the cut made by said cones of said pilot cutter.

8. Structure as specified in claim 4, in which a plane contacting the outwardly projected lower limit of each respective truncated conical cutter, and the adjacent cone of the pilot cutter, is disposed substantially at an angle of 30 degrees with relation to a horizontal plane extending radially with relation to the axis of said body.

9. A reverse circulation rotary drill, including: an open-ended vertically disposed tubular body and having a horizontally disposed flange adjacent its lower end, said body having a flanged upper end adapted to be connected to the lower end of a drill string and rotated therewith; a spindle equipped multiple cone pilot cutter frame rigidly connected to the lower surface of said horizontal flange, said cutter frame having a fluid course therethrough in communication with the bore of said body; a pilot cutter cone journaled by each spindle on said cutter frame; a plurality of support members each rigidly connected at one end to the periphery of said body in equidistant radially spaced relation about its axis and angularly extending outward and downward therefrom intermediate the

ends of said body, said support members terminating in a common horizontal plane at their lower ends in outward equidistant radially spaced relation from said horizontal flange; a like plurality of truncated conical cutters each having a spindle extending between and connected with the lower extremity of each said support member and the periphery of said flange for journaling said truncated cutters, the axis of the respective truncated cutters lying within a conical surface generated about the longitudinal axis of said body, the truncated end of said truncated cutters disposed downwardly against said horizontal flange, said horizontal flange having inwardly directed arcuate recesses between its connections with said truncated cutter spindles for permitting the free passage of fluid downwardly toward the lower end of said body; and means for directing fluid within the drilled bore against the teeth of said truncated cutters in a washing action for cleaning same.

10. Structure as specified in claim 9, in which the means includes a helically disposed web joining the upper end portion of each said support member with the adjacent portion of said body, the depending edge of each said web lying in relatively close spaced relation with the upwardly projecting teeth of each particular truncated conical cutter, whereby rotation of said drill causes said webs to direct fluid within the drilled bore downwardly against said rotating truncated conical cutters.

11. Structure as specified in claim 9, in which the length of each truncated conical cutter is such that the same will make an annular cut slightly overlapping inwardly the cut made by said multiple cone pilot cutter.

12. Structure as specified in claim 9, in which a plane contacting the outwardly projected lower limit of each respective truncated conical cutter, and the adjacent cutter of said multiple cone pilot cutter, is disposed substantially at an angle of 30 degrees with relation to a horizontal plane extending radially with relation to the axis of said body.

13. A reverse circulation rotary drill, including: an open-ended vertically disposed tubular body having a horizontally disposed flange adjacent its lower end, said body having a flanged upper end adapted to be connected to the lower end of a drill string for rotation therewith; a spindle equipped multiple cone pilot cutter frame rigidly connected to the lower surface of said horizontal flange, said cutter frame having a fluid course therethrough in communication with the bore of said body; a pilot cone cutter journaled by each spindle on said cutter frame; a plurality of support members each rigidly connected at one end to the periphery of said body in equidistant

radially spaced relation about its axis and extending angularly outward and downward therefrom intermediate the ends of said body, said support members terminating in a common horizontal plane at their lower ends in outward equidistant radially spaced relation from said flange; a like plurality of spindles extending between and rigidly connected with lower end portion of each respective said support member and the adjacent peripheral portion of said horizontal flange, the axis of the respective spindles lying within a conical surface generated about the longitudinal axis of said body; a like plurality of truncated conical cutters journaled by said spindles and extending between each respective said support member and the adjacent edge of said horizontal flange; 15 longitudinally extending wedge shaped teeth having cutting edges on each said truncated cutter; and means for directing fluid within the drilled bore against the teeth of each said truncated cutter in a washing action for cleaning the same.

20. 14. Structure as specified in claim 13, in which the means includes a helically disposed web joining the upper end portion of each said support member with the adjacent portion of said body, the depending edge of each said web lying in relatively close spaced relation with the upwardly projecting teeth of each particular truncated conical cutter, whereby rotation of said drill causes said webs to direct fluid within the drilled bore downwardly against said rotating truncated conical cutters.

25. 15. Structure as specified in claim 13, in which the length of each truncated conical cutter is such that the same will make an annular cut slightly overlapping inwardly the cut made by said multiple cone pilot cutter.

30. 16. Structure as specified in claim 13, in which a plane contacting the outwardly projected lower limit of each respective truncated conical cutter, and the adjacent cutter of said multiple cone pilot cutter, is disposed substantially at an angle of 30 degrees with relation to a horizontal plane extending radially with relation to the axis of said body.
